(57) **CLAIM**

The ornamental design for a recharging band for wireless clippers, as shown and described.

DESCRIPTION

FIG. 1 is a top, front, left side perspective view of a recharging band for wireless clippers showing our new design;

FIG. 2 is a top, front, left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

In the drawings, the broken lines depict environment subject matter that form no part of the claimed design. The broken line showing a port in FIG. 3 depicts a portion of the recharging band for wireless clippers that forms no part of the claimed design.

1 Claim, 5 Drawing Sheets
